INVENTOR,

Isaac B. MacomberBY Oscar Lapham, ATT'y.

UNITED STATES PATENT OFFICE.

ISAAC B. MACOMBER, OF PORTSMOUTH, RHODE ISLAND.

ANKLE-SUPPORT FOR SKATES.

SPECIFICATION forming part of Letters Patent No. 718,265, dated January 13, 1903.

Application filed May 12, 1902. Serial No. 107,026. (No model.)

To all whom it may concern:

Be it known that I, ISAAC B. MACOMBER, a citizen of the United States, residing at Portsmouth, in the county of Newport, in the State of Rhode Island, have invented a new and useful Improvement in Ankle-Supports for Skates, of which the following is a specification.

My invention relates to that class of supports which are removably attached to the rear standard of the skate-runner, with a leg-band and a supporting-rod extending vertically from the skate-runner along the side of the leg of the wearer; and it consists in an improved clamping device for attaching the supporting-rod to the skate-runner and in improved means for connecting the leg-band to the supporting-rod and for rendering the band adjustable.

In the accompanying drawings, Figure 1 is a broken side view showing the rear end of a skate with the attaching-clamp, the supporting-rod, and the leg-band. Fig. 2 is a top view of the leg-band and the swivel device by means of which it is connected to the supporting-rod. Fig. 3 is a top view of the clamp secured to the rear standard of the skate-runner, the said standard being shown in section. Fig. 4 shows a section of the socket for holding the supporting-rod, taken on the line $x-x$ of Fig. 1. Fig. 5 shows a cross-section of the leg-band, taken on line $y-y$ of Fig. 2. Fig. 6 is a sectional view taken on the line $z-z$ of Fig. 2. Fig. 7 is a detail side view showing the catch for holding the ends of the leg-band together. Fig. 8 is a detail section showing a modification.

In the drawings, a represents the rear portion of the skate-runner, and b the rear standard, to which my improved clamping device c is attached, the said device being formed in two members d and e , which are connected with each other by means of the screw n . The clamping member d is preferably provided with the lateral extensions g , which serve to impart stability to the clamping device when secured to the standard b of the skate-runner. The member d is also provided with the socket h , which is adapted to receive the lower end i of the supporting-rod j , and with the forwardly-extending projection k , which passes through a perforation l ,

made in the end portion l of the member e of the clamp, the opposite end of the said clamping member e being provided with the screw-threaded ear m , adapted to receive the thread of the screw n , which is held in the perforated ear o of the clamping member d , the said member d being also provided with the recess p , which forms a hook at its rear portion adapted to engage with the rear edge q of the standard b , the said standard being provided with the recess or notch r , as shown by the dotted lines in Fig. 1. When the members d and e of the clamping device are secured to the standard b , as shown in the drawings, the bend s of the member e will enter the recess or notch t at the front edge of the standard b , and the clamping device will be firmly held to the standard. The lower end of the supporting-rod j is provided with the annular groove u , which is adapted to receive the point of the screw v , by means of which the end of the supporting-rod is held in its socket h and made adapted for pivotal movement therein, and I prefer to incline the outer face of the recess p at the point w , as shown, and to provide the angle s of the member e with a corresponding inclination x , whereby when the two clamping members are drawn together by means of the screw n the inner faces of the clamping members d and e will be drawn inwardly against the sides of the standard b .

The leg-band a' is made in two parts b' b'' , the part b' being provided with the series of perforations c' c'' and the part b'' provided with a single perforation c'' , the said perforations being adapted to receive the outwardly-projecting stud d' of the band-holding piece e' , which swivels upon the collar f' , adjustably held upon the supporting-rod j by means of the screw g' , which may either be a clamping-screw, as shown in Fig. 2, or a set-screw, as shown in Fig. 8, and by shifting the stud d' into the different perforations of the part b' of the leg-band the said band may be either increased or diminished in size, as desired. The part b' of the leg-band is also provided with the catch projection h' , which is adapted for engagement with the perforation i' , made in the overlapping part b'' of the band. The swivel-piece e' is held upon the adjustable collar f' by means of the flange j' , as shown in Fig. 8.

I claim as my invention—

1. In an ankle-support for skates, the combination of the leg-band a' , and the supporting-rod j , with the clamping device c , comprising the clamping members d and e and the clamping-screw n , and having a loose socket connection with the supporting-rod, one of the said clamping members being provided with the forwardly-extending projection k , and the other with the receiving-perforation k' , substantially as described.
2. In an ankle-support for skates, the combination of the clamp member d , provided with the socket h , and the forward projection k , with the clamp member e , provided with the perforation k' , adapted to receive the projection k , and the clamping-screw n , substantially as described.
3. In an ankle-support for skates, the combination of the clamp member d , provided with the socket h , the forward projection k , and the inclined surface w , with the clamp

member e , provided with the perforation k' , adapted to receive the projection k , and with the inclined surface w , and the clamping-screw n , substantially as described.

4. In an ankle-support for skates, the combination of the adjustable leg-band a' , provided with the perforations e' , with the swivel-piece e' , provided with the engaging stud d' , the adjustable collar f' , and the supporting-rod j , substantially as described.

5. In an ankle-support for skates, the combination of the supporting-rod j , the adjustable collar f' , and the swivel-piece e' , connected therewith, with the leg-band a' , formed of the two parts b' and b^2 , held together upon the stud d' of the swivel-piece, and provided with locking means at their engaging ends, substantially as described.

ISAAC B. MACOMBER.
